UNITED STATES PATENT OFFICE.

HENRI COLOMB, OF TAVANNES, SWITZERLAND.

WINDING-UP AND HAND-SETTING MECHANISM IN WATCHES.

Application filed December 23, 1924. Serial No. 757,707.

To all whom it may concern:

Be it known that I, HENRI COLOMB, citizen of Switzerland, residing at Pension Economique Building, Tavannes, Canton of 5 Bern, Switzerland, have invented certain new and useful Improvements in Winding-Up and Hand-Setting Mechanisms in Watches, of which the following is a specification.

10 This invention relates to improvements in winding and setting mechanism for watches.

Heretofore two kinds of winding and hand setting mechanisms operated by the 15 stem were known. They were called "positive" if the rocking lever forming part of the mechanism was moved to setting position by hand and "negative" if the rocking lever was moved to setting position by means 20 of a spring. The last named arrangement is preferred in the United States of America, because by its use it is possible to make the winding stem in two parts which move together when winding, and the outer one of 25 which moves independently of the inner one during setting. The inner section of the stem in this type forms part of the watch movement, while the outer section is connected to the casing, so that the two pieces, 30 movement and casing may be transported and sold separately.

Up to the present time, for each type of winding and hand setting mechanism, two working forms had to be created by the 35 manufacturer, one form for each kind, and therefore two types of rough movements were necessary having plates with differently arranged holes for pivots and fixing screws, etc., which varied not only in number 40 but also shape.

The primary object of the present invention is to simplify the manufacturing of watches of the two types and this is accomplished by using identical parts for each 45 type of winding and setting mechanism, with the holes for the pivots and fixing screws identically arranged in both types, the only difference being that springs of different shapes must be employed for the two 50 types of mechanism. However, even for these differently shaped springs, the holes for the fixing screws are identically arranged in both movement plates.

55 The invention is illustrated in the accompanying drawing in which:

Figure 1 is a fragmentary view of a

"positive" winding and setting mechanism; and

Figure 2 is a similar view of a "negative" winding and setting mechanism. 60

Referring to both views it will be noted that the watch movement plates are the same in both types and each plate has a counter-sinker or cavity *m* to house a certain part of the mechanism. When the plate is 65 manufactured, it will be provided with the necessary holes for the pivot pins, screws, etc., and it is to be noted that these holes will be arranged the same for both types of 70 watches. *a* designates a slidable sleeve arranged on the stem and provided at its inner end with contrate teeth to engage the setting gear *d'* and provided at its opposite end with clutch teeth to engage similar clutch teeth on the winding gear *d*. The 75 sleeve *a* has a circumferential groove engaged by the rocking lever *c* which is pivotally mounted at *c'*. This lever is engaged by a leaf spring *b* which normally tends to push the lever outwardly so that the clutch 80 teeth of the sleeve *a* will engage the clutch teeth of the winding gear *d*. The lever *c* may be moved in the opposite direction by a double armed lever *e* pivotally mounted at *f*. This double armed lever is provided 85 at its opposite ends with projecting pins *h* and *h'*.

Referring now to Figure 1, which illustrates the "positive" type, it may be seen that a spring *i* is connected to the movement 90 plate by screws *x* and the free arm *y* of this spring has two notches to engage the pin *h* of the lever *e*. In this type the winding stem *g* is normally in its inner position as shown in Figure 1 and with the parts in 95 this position the spring *b* causes the lever *c* to hold the clutch teeth of the sleeve *a* in engagement with the clutch teeth of the winding gear *d*, so that each time the stem is turned the watch spring will be wound. 100 When the watch is to be set, the stem *g* is pulled outwardly in the direction of the arrow and as the stem is connected to the lever *e*, this lever will be turned in a clockwise direction to move the pin *h* from the first notch in the end *y* of the spring to the 105 second notch in said spring. At the same time the lower end of the lever *e* will ride on the free end of the lever *c* and move this lever in a clockwise direction against the force of the spring *b* and cause the conrate teeth of the sleeve *a* to engage the setting 110

gear d' . Then when the stem g is turned the hands of the watch will be set.

As before stated, the mechanism in Fig. 2 is exactly the same as that shown in Fig. 1 with the exception that a spring k of slightly different form is used instead of the spring i . The spring k is secured in position by screws α which will occupy holes arranged exactly the same as in Fig. 1. In Fig. 2 the watch stem is made of two parts, the inner one g' only being shown in the drawing. Stems of this character are well known and the outer section of the stem normally functions to hold the lever e in the position shown in Fig. 1, that is, with the end of the spring k bearing against the pin h' and tending to move the lever e in a clockwise direction. When, however, the outer end of the stem is moved outwardly the lever e is released so that the spring k swings the lever e in a clockwise direction and causes the lever c to move into the posi-

tion shown in Figure 2 and thus bring the sleeve α into position to set the watch.

From the foregoing it may be seen that a watch movement may be made up to form either a "positive" or "negative" type and the hand setting and winding mechanism may be provided for either type by simply adding the proper spring i or k .

What I claim and desire to secure by Letters-Patent is:

In a watch winding and setting mechanism, a movement plate, a double armed lever pivotally mounted on said plate and provided at its opposite ends with projecting pins, and means connected to said plate for attaching a spring to the latter to engage either one of said pins, for either a positive or negative type of winding and setting mechanism.

In testimony whereof I affix my signature.

HENRI COLOMB.
